CLAIM

The ornamental design for a surveillance camera, as shown and described.

DESCRIPTION

FIG. 1 is a front perspective view of a surveillance camera showing our new design;

FIG. 2 is a front elevational view of the surveillance camera;
FIG. 3 is a rear elevational view of the surveillance camera;
FIG. 4 is a left side elevational view of the surveillance camera;

FIG. 5 is a right side elevational view of the surveillance camera;

FIG. 6 is a top plan view of the surveillance camera; and,
FIG. 7 is a bottom view of the surveillance camera.

(Continued)

The broken lines depict no portions of the surveillance camera in which the design is embodied that from no part of the claimed design.

1 Claim, 7 Drawing Sheets
